(57) **CLAIM**

The ornamental design for a moisture absorbing container, as shown and described.

DESCRIPTION

FIG. 1 is a rear perspective view of the moisture absorbing container of the subject invention;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof;

FIG. 8 is a front perspective view thereof;

FIG. 9 is a front perspective view thereof, shown with the membrane and seal installed and the cover removed;

FIG. 10 is a front perspective view thereof, with the seal removed and the membrane and cover installed; and,

FIG. 11 is a front perspective view thereof, with the cover and the seal removed.
